COMBINED COVER AND HOLDER FOR A REFUSE BAG

John C. Brighton, Columbus, Ind., assignor to Arvin
Industries, Inc., Columbus, Ind., a corporation of Indiana

Filed Oct. 8, 1962, Ser. No. 72,040

Term of patent 14 years

(Cl. D58—17)

FIG. 1 is a perspective view of a combined cover and holder for a refuse bag embodying my new design;

FIG. 2 is a side elevation thereof, but showing the cover in raised position;

FIG. 3 is a rear elevation thereof, but showing a bag attached thereto; and

FIG. 4 is a top plan view thereof, but showing a bag attached thereto the cover in raised position.

The portions shown in broken lines are for illustrative purposes only.

I claim:

The ornamental design for a combined cover and holder for a refuse bag, as shown and described.
